UNITED STATES PATENT OFFICE.

SAMUEL M. KEKUEWA, OF LAHAINA, TERRITORY OF HAWAII.

SPOUT.

1,192,068.

Specification of Letters Patent. Patented July 25, 1916.

Application filed September 25, 1915. Serial No. 52,661.

To all whom it may concern:

Be it known that I, SAMUEL M. KEKUEWA, a citizen of the United States, residing at Lahaina, in the District of Lahaina, Maui, Territory of Hawaii, have invented certain new and useful Improvements in Spouts; and I do hereby declare the following to be a full, clear, and exact description of the invention, such as will 10 enable others skilled in the art to which it appertains to make and use the same.

The present invention is directed to improvements in spouts, and has for its object to provide a device of this character especially adapted to be attached to the side 15 of an oil can, or the like.

A further object of the invention is to provide a spout, constructed in such a manner that the same can be manipulated to cut 20 off or regulate the flow of liquid from the can.

A still further object of the invention is to provide a spout of this character which is exceedingly simple in construction, efficient in operation, and one which can be 25 easily and quickly attached to a conventional form of oil can.

With these and other objects in view, this invention resides in the novel features 30 of construction, formation, combination and arrangement of parts to be hereinafter more fully described, claimed and illustrated in the accompanying drawing, in which:—

Figure 1 is a fragmentary side elevation 35 of the can equipped with the spout. Fig. 2 is a longitudinal sectional view through the same. Fig. 3 is a sectional view on line 3—3 of Fig. 2. Fig. 4 is a detail perspective view of the seat.

Referring to the drawing 1 indicates the can, which is provided with the usual pouring spout 2, which in this instance serves as 40 means for venting the can.

The improved spout consists of a circular 45 plate 3, which is adapted to be soldered to one side of the can 1, and adjacent the top thereof, said plate being provided with a central opening 4, in which is secured an exteriorly threaded sleeve 5, the purpose of 50 which will appear later. The can body 1 is cut to provide an opening 6, and into which projects the seat 7, said seat being formed from a strip of sheet metal and bent into U-shape. The arms 8 of the seat ter-

minate at their outer ends in right angle 55 extensions 9, which are soldered to the inner surface of the plate 3, and have their inner faces resting against the can body when the plate is fixed to the can, and as clearly shown in Fig. 2 of the drawing. 60

The spout 10 comprises a cylindrical hollow body 11, said body being exteriorly threaded for engaging the threads of the sleeve 5. To facilitate rotation of the body 11, a head 12 is secured in any suitable manner to the outer end thereof. The inner end of the body has mounted thereon a collar 13, which is adapted to engage the packing 14, said packing being mounted in the seat 7, and may be formed from leather, or 65 any other suitable material. It is obvious that when the body 11 is screwed inwardly that the inner end thereof will impinge against the packing, thus cutting off the flow of liquid from the can. The body may 70 be adjusted toward or away from the packing to increase or decrease the flow of liquid, as desired.

What is claimed is:—

1. In combination with a can having an 80 opening formed in its side, of a plate adapted to be attached to the can, a seat carried by the plate and projecting into said opening, a packing carried by the seat, a sleeve engaged centrally of the plate, a spout having threaded engagement with the sleeve, said spout having its inner end adapted to engage the packing, as and for the purpose set forth.

2. In combination with a can having an 90 opening formed therein, of a plate adapted to be secured exteriorly of the can, a sleeve engaged centrally of the plate, a seat carried by the plate and projecting through said opening, a spout comprising a hollow 95 body having threaded engagement with said sleeve, a packing carried by the seat and adapted to be engaged by the inner end of the spout body, a head fixed to the outer end of the spout body, as and for the purpose 100 set forth.

In testimony whereof, I affix my signature, in the presence of two witnesses.

SAMUEL M. KEKUEWA.
